CHEMICAL PROCESS

Harold S. Holt, Wilmington, Del., assignor to E. I.
du Pont de Nemours & Company, Wilmington,
Del., a corporation of Delaware

No Drawing. Application January 14, 1938,
Serial No. 184,969

11 Claims. (Cl. 196—13)

This invention relates to the separation of mixtures of hydrocarbons by selective solvent extraction and more particularly to the solvent refining of mineral oils.

It is now well known that a large proportion of the mineral oils and gasolines of today are complex mixtures of paraffinic and non-paraffinic hydrocarbons. It is frequently desirable to separate the non-paraffinic hydrocarbons from the paraffinic hydrocarbons for various reasons. One of the main reasons is that the paraffinic hydrocarbons are in general more resistant to decomposition through heat and oxidation than the non-paraffinic hydrocarbons. Accordingly, the oil containing the larger proportion of paraffinic constituents or, in other words, the relatively more paraffinic oils are more stable than the less paraffinic oils and hence are more desirable as lubricants and for other purposes.

Various methods have been proposed for separating the non-paraffinic from the paraffinic constituents of oils. One of the more common and oldest is by treatment with sulfuric acid which removes some of the non-paraffinic compounds from the oils. More recently it has been proposed to separate the non-paraffinic hydrocarbons by means of selective solvent extraction.

An object of the present invention is to provide a method for separating a mixture of paraffinic and non-paraffinic hydrocarbons into portions, one of which is relatively more paraffinic than the original mixture and the other relatively less paraffinic. Another object is the separation of relatively non-paraffinic bodies from mineral lubricating oils to produce lubricating oils of relatively high paraffinic character. A further object is the production of lubricating oils with improved viscosity-temperature curves from oils with poor viscosity-temperature curves. Still other objects will appear hereinafter.

These objects may be accomplished in accordance with my invention which comprises treating the mixtures of paraffinic and non-paraffinic hydrocarbons with an alcohol having the following general formula:

in which R and R₁ may be hydrogen atoms or hydrocarbon radicals and the total number of carbon atoms in R and R₁ taken together when either or both are hydrocarbon radicals is less than 7.

The hydrocarbon mixture or oil is mixed with a solvent comprising an alcohol of the formula noted above under such conditions that two layers are formed; one of which comprises the constituents which it is desired to extract from the oil dissolved in the bulk of the solvent, and the other layer comprises the undissolved and relatively paraffinic hydrocarbons in admixture with a relatively small amount of the solvent. Preferably, my method comprises mixing the said alcohol and hydrocarbon mixture in approximately equal volumes and heating same with agitation at the temperature at which the solvent and oil become completely miscible. This solution is then cooled while agitating and the cooling continued to a temperature at least 20° below the temperature of complete miscibility. The resulting mixture is then allowed to stand until it separates into two layers. These layers are separately withdrawn and the alcohol recovered from each by distillation, preferably under reduced pressure. The residue from the layer containing the larger amount of solvent consists of a large portion of the non-paraffinic constituents; whereas the layer containing a smaller amount of solvent consists primarily of the paraffinic constituents.

In the examples given below, the selective removal of non-paraffinic constituents from a mineral oil has been measured by following the change in viscosity-gravity constant of the oil. This constant has been described by J. B. Hill and H. B. Coates in Industrial and Engineering Chemistry, volume 20, page 641, et. seq., in an article entitled "The Viscosity-Gravity Constant of Petroleum Lubricating Oils". If a given crude petroleum be distilled into successive fractions and the specific gravities and viscosities of the several fractions determined, it will be found that they conform to the general relationship:

$$G = a + \frac{1.0752 - a}{10} \log (V - 38)$$

in which "G" is the specific gravity at 60° F., "V" is Saybolt Universal viscosity at 100° F., and "a" is the viscosity-gravity constant. These constants are lower for fractions of the naphthenic crudes. The viscosity-gravity constant is, therefore, an index of the paraffinity of an oil, and a decrease in the value of this constant for a given fraction of lubricating oil indicates an increase in paraffin hydrocarbon content.

The following examples set forth certain well defined instances of the application of this invention. They are, however, not to be considered as limitations thereof, since many varia-

tions may be made without departing from the spirit and scope of this invention.

Example 1

5 A lubricating oil distillate (with the following characteristics: viscosity at 100° F., 566 secs. Saybolt Universal; specific gravity at 60° F./60° F., 0.927; viscosity-gravity constant, 0.872;

n_D^{20}

10 1.5140) was mixed with an equal volume of dimethyl ethynyl carbinol, heated with agitation to 100° C. at which temperature solvent and oil were miscible, the solution cooled to 25° C., allowed to settle, and the two layers withdrawn into separate 15 containers. Dimethyl ethynyl carbinol was removed from both layers under reduced pressure. The top layer was found to contain 70 percent of the volume of the original oil, which had the following characteristics: viscosity-gravity constant, 20 0.866;

n_D^{20}

1.5098.

Example 2

25 The lubricating oil distillate given in Example 1 was heated to 50° C. with an equal volume of isopropyl ethynyl carbinol with agitation, cooled to 20° C., and allowed to settle 15 hours. The two 30 layers which formed were treated as in Example 1, with an oil recovery in the bottom layer of 72 per cent. This oil had characteristics as follows: viscosity-gravity constant, 0.858;

n_D^{20}

35 1.5047.

Example 3

40 The distillate used in Example 1 was mixed with an equal volume of methyl ethyl ethynyl carbinol at 35° C. and then allowed to settle 15 hours at approximately 4° C. After separation and removal of the solvent from each layer, an oil recovery of 73 per cent was obtained from the 45 top layer. This oil had the following characteristics: viscosity-gravity constant, 0.868;

n_D^{20}

1.5110.

50 Acetylenic carbinols may, if desired, be used with advantage in conjunction with other solvents which are known to possess selective solvent action in petroleum refining. In such admixtures, acetylenic carbinols materially lower the temperatures of miscibility and separation of 55 the solvent with which they are used and thus permit greater flexibility in the operation of the solvent refining process. The following example serves as an illustration.

60 *Example 4*

A solvent was prepared by mixing one part of methyl ethyl ethynyl carbinol with one part of beta-beta' dichlorodiethyl ether. The lubricating oil distillate given in Example 1 was heated with an equal volume of this mixed solvent to 30° C., the temperature of complete miscibility. The solution was cooled to 5° C., settled four hours, and the separated layers treated as in the previous examples. From the top layer a yield of 73 per cent of oil was obtained having a viscosity-gravity constant of 0.855. Under the same conditions of treatment, equal volumes of the lubricating oil distillate and dichlorodiethyl ether were 75 miscible only at the higher temperature of 55°

C., the yields of oil in this case being 71.6 per cent and the viscosity-gravity constant being 0.856.

As examples of other alcohols which fall within the class adapted for use in this process, one may use methyl ethynyl carbinol (B. P. 107-109° C.), ethyl ethynyl carbinol (B. P. 122-125° C.), and ethynyl cyclohexanol (B. P. 97-103° C./65 mm.).

The conditions of application of the solvent will vary with the nature of the oil, highly naphthenic oils in general requiring a lower temperature of separation than highly paraffinic oils. The temperatures employed, however, may be expected to range from about 0° C. to 200° C. or thereabouts. For some oils they may be expected 15 to be somewhat lower than 0° C. The volume ratio of solvent to oil may be varied within wide limits and will be determined by the nature of the crude distillate and by the quality desired in the refined oil. In general, the limits of the ratio 20 of solvent to oil may lie between about 1:10 and about 5:1. Application of the solvent is not limited, of course, to single batch extractions but may employ any other suitable means, for example, countercurrent extraction. Extraction 25 with ethynyl carbinols need not be confined to lubricating oil distillates but may be extended to include other hydrocarbon or mineral oil fractions such as cracked naphthas whose boiling range is sufficiently different from the solvent to 30 permit separation of the carbinol.

In fact the method disclosed herein may be used in connection with the separation of paraffinic and non-paraffinic hydrocarbons in any hydrocarbon mixture containing same.

In the example given covering the use of mixtures of ethynyl carbinols with other selective solvents, it will be noted that the chief effect of the carbinol is to lower the miscibility temperature. Examples of other solvents which might be used in combination with an acetylenic carbinol are nitrobenzene, aniline, furfural, dialkyl 40 formamides, phenol, and cresylic acids.

Extraction treatment with ethynyl carbinols or mixtures containing them may be applied to raw distillates or to a partially refined product. Under certain conditions, for example, in the case of oils with high sulfur content or poor sludging characteristics, it may be desirable to supplement the solvent extraction with the usual acid, alkali, 45 doctor, or clay treatment, applied either before or after the extraction.

The advantages of the present invention are:

(1) The production of high grade lubricating 55 oil from mediocre crudes with negligible refining loss compared to the ordinary acid-alkali process.

(2) The increasing of the paraffinic content of a hydrocarbon mixture containing paraffinic and non-paraffinic hydrocarbons by the removal of 60 some of the non-paraffinic hydrocarbons therefrom.

(3) Combinations of acetylenic carbinols with other selective solvents result in lowering of miscibility temperatures with substantially the same 65 yield and quality of raffinate, thereby permitting operation of the solvent extraction processes under favorable conditions for heat-susceptible oils.

It is apparent that many widely different embodiments of this invention may be made without departing from the spirit and scope thereof, therefore it is not intended that the invention be limited except as defined by the appended claims.

1. The method of treating a normally liquid hydrocarbon mixture containing relatively paraffinic and relatively non-paraffinic compounds which comprises extracting the hydrocarbon mixture with a solvent comprising an alcohol having the general formula:

10

wherein R and R_1 are selected from the group consisting of hydrogen and hydrocarbon radicals, and wherein the total number of carbon atoms in R and R_1 is less than 7.

- 15 2. The process in accordance with claim 1 characterized in that the alcohol is isopropyl ethynyl carbinol.

- 20 3. The method of treating a normally liquid hydrocarbon mixture containing relatively paraffinic and relatively non-paraffinic compounds so as to separate at least a portion of said relatively non-paraffinic compounds from admixture with said relatively paraffinic compounds which comprises commingling with said hydrocarbon 25 mixture a solvent comprising an alcohol of the general formula

30

wherein R and R_1 are selected from the group consisting of hydrogen or hydrocarbon radicals and wherein the total number of carbon atoms in R and R_1 is less than 7, causing the resulting mixture to separate into two layers, separating the two layers, and recovering the hydrocarbon fraction contained in each layer.

- 35 4. The process in accordance with claim 3 characterized in that the ratio of the oil to the extracting solvent is between about 1 to 10 and about 5 to 1.

- 40 5. The method of treating a normally liquid hydrocarbon mixture containing relatively paraffinic and relatively non-paraffinic compounds 45 so as to separate at least a portion of said relatively non-paraffinic compounds from admixture with said relatively paraffinic compounds which comprises commingling with said hydrocarbon

mixture in approximately equal volume an alcohol having the general formula:

5

wherein R and R_1 are selected from the group consisting of hydrogen and hydrocarbon radicals and wherein the total number of carbon atoms in R and R_1 is less than 7, heating said mixture to a temperature at which the hydrocarbon mixture and alcohol becomes miscible, then cooling said mixture while agitating to at least 20° below the temperature of complete miscibility causing the resulting mixture to separate into two layers, 15 separating the two layers, and recovering the hydrocarbon fraction contained in each layer.

- 20 6. The process in accordance with claim 5 characterized in that the alcohol is isopropyl ethynyl carbinol.

- 25 7. The method of treating a normally liquid hydrocarbon mixture containing relatively paraffinic and relatively non-paraffinic compounds so as to separate at least a portion of said relatively non-paraffinic compounds from admixture 30 with said relatively paraffinic compounds which comprises commingling with said hydrocarbon mixture an approximately equal volume of isopropyl ethynyl carbinol at a temperature of about 50° C., then cooling said mixture to about 35 20° C. while agitating, allowing the resulting mixture to separate into two layers, separating the two layers and recovering the hydrocarbon fraction contained in each layer.

- 35 8. The process in accordance with claim 1 characterized in that the alcohol is dimethyl-ethynyl carbinol.

- 40 9. The process in accordance with claim 1 characterized in that the alcohol is methyl-ethylethynyl carbinol.

- 45 10. The process in accordance with claim 5 characterized in that the alcohol is dimethyl-ethynyl carbinol.

11. The process in accordance with claim 5 characterized in that the alcohol is methylethyl-ethynyl carbinol.

1. The method of treating a normally liquid hydrocarbon mixture containing relatively paraffinic and relatively non-paraffinic compounds which comprises extracting the hydrocarbon mixture with a solvent comprising an alcohol having the general formula:

10

wherein R and R_1 are selected from the group consisting of hydrogen and hydrocarbon radicals, and wherein the total number of carbon atoms in R and R_1 is less than 7.

- 15 2. The process in accordance with claim 1 characterized in that the alcohol is isopropyl ethynyl carbinol.

- 20 3. The method of treating a normally liquid hydrocarbon mixture containing relatively paraffinic and relatively non-paraffinic compounds so as to separate at least a portion of said relatively non-paraffinic compounds from admixture with said relatively paraffinic compounds which comprises commingling with said hydrocarbon 25 mixture a solvent comprising an alcohol of the general formula

30

wherein R and R_1 are selected from the group consisting of hydrogen or hydrocarbon radicals and wherein the total number of carbon atoms in R and R_1 is less than 7, causing the resulting mixture to separate into two layers, separating the two layers, and recovering the hydrocarbon fraction contained in each layer.

- 35 4. The process in accordance with claim 3 characterized in that the ratio of the oil to the extracting solvent is between about 1 to 10 and about 5 to 1.

- 40 5. The method of treating a normally liquid hydrocarbon mixture containing relatively paraffinic and relatively non-paraffinic compounds 45 so as to separate at least a portion of said relatively non-paraffinic compounds from admixture with said relatively paraffinic compounds which comprises commingling with said hydrocarbon

mixture in approximately equal volume an alcohol having the general formula:

5

wherein R and R_1 are selected from the group consisting of hydrogen and hydrocarbon radicals and wherein the total number of carbon atoms in R and R_1 is less than 7, heating said mixture to a temperature at which the hydrocarbon mixture and alcohol becomes miscible, then cooling said mixture while agitating to at least 20° below the temperature of complete miscibility causing the resulting mixture to separate into two layers, 15 separating the two layers, and recovering the hydrocarbon fraction contained in each layer.

- 20 6. The process in accordance with claim 5 characterized in that the alcohol is isopropyl ethynyl carbinol.

- 25 7. The method of treating a normally liquid hydrocarbon mixture containing relatively paraffinic and relatively non-paraffinic compounds so as to separate at least a portion of said relatively non-paraffinic compounds from admixture with said relatively paraffinic compounds which comprises commingling with said hydrocarbon mixture an approximately equal volume of isopropyl ethynyl carbinol at a temperature of about 50° C., then cooling said mixture to about 30 20° C. while agitating, allowing the resulting mixture to separate into two layers, separating the two layers and recovering the hydrocarbon fraction contained in each layer.

- 35 8. The process in accordance with claim 1 characterized in that the alcohol is dimethyl-ethynyl carbinol.

- 40 9. The process in accordance with claim 1 characterized in that the alcohol is methyl-ethylethynyl carbinol.

- 45 10. The process in accordance with claim 5 characterized in that the alcohol is dimethyl-ethynyl carbinol.

11. The process in accordance with claim 5 characterized in that the alcohol is methylethyl-ethynyl carbinol.
